UNITED STATES PATENT OFFICE.

JOHN W. RANKIN, OF MONTREAL, QUEBEC, CANADA, ASSIGNOR TO CANADIAN CAR & FOUNDRY COMPANY, LIMITED, OF MONTREAL, CANADA.

BOLSTER END MEMBER.

1,151,040.

Specification of Letters Patent. Patented Aug. 24, 1915.

Application filed December 21, 1914. Serial No. 878,397.

To all whom it may concern:

Be it known that I, JOHN W. RANKIN, a citizen of the Dominion of Canada, and resident of the city of Montreal, in the 5 Province of Quebec and Dominion of Canada, have invented certain new and useful Improvements in Bolster End Members, of which the following is a full, clear, and exact description.

10 This invention relates to improvements in bolster end members, and the object is to provide an end member having a wearing plate of harder material inserted therein where the end member bears in the truck 15 side frame.

A further object is to provide a bolster end member and wearing plate of simplified construction, so arranged that the wearing plate may be inserted with a minimum expenditure of time, and will be very securely held.

The device consists essentially of an end member of any suitable type having a shallow pocket formed therein at the point of engagement with the truck frame. This 25 pocket opens at the inner end of the member and connects at the outer end with a small passage formed through the guide flange. The wear plate, which is provided 30 with a suitable tongue, is inserted in the pocket from the inner end, the tongue passing through the flange passage and being clenched over the flange to prevent the plate backing out.

35 In the drawings which illustrate the invention:—Figure 1 is a side elevation of a bolster end member with the improved wear plate in position. Fig. 2 is a half plan view of the end member. Fig. 3 is a half cross section on the line 3—3, Fig. 1.

Referring more particularly to the drawings, 5 designates a bolster end member of any suitable form having side plates 6 provided adjacent the outer end with a guide 45 flange 7 and adjacent the inner end with guide lugs 8, said flange and lugs embracing between them the truck frame. The side plate is provided with a shallow pocket 9 extending from the flange 7 toward the inner end of the plate. This pocket is bounded at the upper and lower edges of the plate by low ribs 10, which may be so low that the wear plate will project above them. The adjacent portions of the lugs 8 are under-

cut, as shown at 11, in line with the adjacent edges of the ribs 10, thus forming straight upper and lower edges for the pocket. One or more slots 12 are formed through the flange 7 in the plane of the pocket 9.

The wear plate 13 is a rectangular sheet of metal, preferably slightly thicker than the ribs 10 and provided with a tongue 14 adapted to pass through the slot 12, and be clenched over on the flange 7, as clearly 55 shown in Figs. 1 and 2. The plate 13 is thus held against backing out of the pocket and cannot move forwardly on account of the flange 7, which it abuts. Vertical movement is checked by the ribs 10 and movement 60 away from the side plate is prevented by the overlapping portions of the lugs 8 and the engagement of the tongue in the slot.

The operation of inserting a wear plate is extremely simple. The plate is slipped 75 tongue end first under the overhanging lugs 8 and advanced until the tongue passes through the slot 12 and the end of the plate abuts the flange 7. The tongue is then clenched over and the operation is complete. 80

From the foregoing description, it will be obvious that the cost of making and inserting a wearing plate is reduced to a minimum. Worn plates may be very quickly and easily exchanged for fresh ones. The casting of 85 the end member as arranged for the reception of this plate presents no complications, and the additional cost is practically negligible. The lugs 8 may if desired be continued in a vertical direction so as to meet 90 and form a continuous bearing flange, but it is doubtful if such structure would have any advantage.

Having thus described my invention, what I claim is:—

95 1. A bolster end member having pockets in the sides thereof opening toward the inner end of the member and slotted guide flanges adjacent the outer ends of said member, and wearing plates inserted in said 100 pockets projecting through the flange passages and clenched over the flanges.

2. A device of the character described, comprising a bolster end member having side plates provided at their outer ends with 105 slotted flanges, undercut lugs at the inner ends of said side plates, ribs on the side plates between the lugs and flanges, and

wearing plates passing under the lugs and between the ribs and projecting through the flange slots.

3. A device of the character described, comprising a bolster end member, wearing plates of harder material on the sides thereof, guide flanges on the sides of said member forming abutments for said plates, top and bottom plate holding ribs on the member, top and bottom guide lugs overlapping and holding said plate, and tongues on the plate passing through and clenched over the guide flanges.

4. A device of the character described, comprising the combination with a bolster end member, of wear plates of harder material, abutments for said plates formed on

the sides of the member and holding the plates against vertical movement and horizontal movement in one direction, tongues 20 on said plates passing through and folded over the member and holding the plates against movement in a second horizontal direction, and lugs on the member overlapping said plates and coöperating with the 25 tongues thereof to hold the plates against movement away from the member.

In witness whereof, I have hereunto set my hand, in the presence of two witnesses.

JOHN W. RANKIN.
